Primary Examiner — Austin Murphy

(57) **CLAIM**

The ornamental design for a mouse, as shown and described.

DESCRIPTION

FIG. 1 is a front perspective view of a mouse showing our new design;

FIG. 2 is a top perspective view thereof;

FIG. 3 is a front view thereof;

FIG. 4 is a back view thereof;

FIG. 5 is a top view thereof;

FIG. 6 is a bottom view thereof;

FIG. 7 is a right view thereof; and,

FIG. 8 is a left view thereof.

The broken lines in drawings show portions of the mouse that form no part of the claimed design.
